UNITED STATES PATENT OFFICE.

EDWARD B. ALLEN, OF ELIZABETH, NEW JERSEY, ASSIGNOR TO THE SINGER MANUFACTURING COMPANY, OF NEW JERSEY.

SEWING-MACHINE TRIMMER.

SPECIFICATION forming part of Letters Patent No. 598,334, dated February 1, 1898.

Application filed June 15, 1897. Serial No. 641,075. (No model.)

To all whom it may concern:

Be it known that I, EDWARD B. ALLEN, a citizen of the United States, residing at Elizabeth, in the county of Union and State of New Jersey, have invented certain new and useful Improvements in Sewing-Machine Trimmers, of which the following is a specification, reference being had therein to the accompanying drawings.

10 This invention relates to certain improvements on the sewing-machine trimmer embraced by my United States Patent No. 579,632, issued March 30, 1897, the object of the present invention being to improve the 15 shear-trimmer, to provide means for more effectively preventing lint or trimmings from working down through the trimmer slot or opening in the work-plate than could be done with my former construction, and also to provide an adjustable feed-dog section which 20 will be moved laterally with the trimmer when the latter is adjusted to vary the distance between the line of trimming and the line of stitching, so that there will be no difficulty 25 in "chaining off" the last stitches of a seam when the trimmer is adjusted farthest from the needle of the machine.

In the accompanying drawings, Figure 1 is 30 a plan view of the lower part of a Singer single-thread chain-stitch sewing-machine embodying my invention. Fig. 2 is a similar view of the same with the work-plate removed. Fig. 3 is an end view of the same with the work-plate in section. Fig. 4 is a section on line 4 4 of Fig. 2. Fig. 5 is a detail sectional view of the feed-dog and of the adjustable device for securing the lower blade in place.

A denotes a portion of the frame of the machine, and B the rotating driving-shaft, carrying the single-thread chain-stitch looper b 40 and the feed and trimmer operating eccentrics.

C is the feed-bar, carrying the feed-dog c', said bar being jointed at c² to the upwardly-extending arms d of a feed-operating rock-shaft D, having at its rear end an arm d', to which is adjustably connected one end of a pitman d², the other end of which is provided with a strap d³, surrounding an eccentric on 45 the shaft B, and which eccentric, through

said pitman, imparts rocking or feeding movements to said shaft D. The feed-bar is forked at c³ to embrace a feed raising and lowering eccentric on said shaft B.

E is the rocking trimmer-shaft, mounted, 55 as before, in the feed-bar C, carrying the feed-dog c', and provided with a rigid arm e, forked to embrace an eccentric b' on the shaft B to impart rocking movements to said trimmer-shaft. Said trimmer-shaft is also provided 60 with a rigid arm or plate e', (preferably formed rigid therewith,) tapped at its upper end for the reception of set-screw e², by means of which and the clamping-plate and guard e³ the segmental upper shear blade or knife e⁴ 65 is held in any desired position of adjustment, said blade being pivotally mounted on the said shaft E, so that its position may be changed to compensate for wear. The lower trimmer-blade e⁵ is also pivotally mounted on 70 the shaft E, so that it may be adjusted to compensate for wear, and is normally held rigid with or stationary relative to the feed-bar and feed-dog. To this end a rear extension e⁶ of said blade is provided with a slot e⁷ 75 to embrace an adjustable hollow pin or sleeve e¹⁴, formed integral with and extending outward from a slide e⁸, movable in an undercut groove c⁴, formed in the side of the feed-bar C, said hollow pin or sleeve being tapped for 80 the reception of a set-screw e⁹, which impinges, to hold the said slide and sleeve in place, against the bottom of the slot c⁴.

F is a sliding block movable in a suitable guideway in the frame of the machine and 85 provided with a notch or recess f, entered by a depending lug e¹⁰, formed on the hub e¹¹ of the arm e of the rock-shaft E. The block F is provided with a depending lug f', entering an annular groove formed between flanges g 90 on an adjusting-screw G, tapped in the machine-frame and provided with a milled head g', by which it may be readily turned to adjust the trimmer rock-shaft E and the trimmer-blades e⁴ and e⁵, mounted on said shaft, 95 laterally or toward and from the needle. The block F and the trimmer connected therewith are held in any desired position of adjustment against accidental displacement by any suitable retaining device, which in the present in- 100

stance consists simply of the friction-washer f^2 , placed beneath the head of the steadyng or holding screw f^3 .

- H is a sliding lint-guard plate suitably mounted to be moved back and forth or from and toward the needle on the work-plate A', the forward end of said guard-plate being closely adjacent to the arm or plate e' of the trimmer-shaft E, so that there will be no appreciable opening for the passage of lint between the forward end of said guard-plate and the arm or plate e' . The sliding block F is provided with an upwardly-projecting lug f^4 , which enters a slot in the plate H, so that the latter will be adjusted back and forth with the trimmer, which is movable with said block, as has been described. This adjustable lint-guard H is similar to the lint-guard I of my Patent No. 579,632 referred to; but in the machine shown by said patent no provision was made for keeping the front side of the slot in the work-plate closed when the trimmer was adjusted away from the needle. This omission is remedied in the present instance by extending the lint-guard around to the front or outer side of the trimmer, and for convenience in getting at the trimmer-blades when it is necessary to remove the same for sharpening this extension of the lint-guard consists, preferably, of an independent plate H', removably mounted on the plate H by means of the arm h, having holes to engage the upper ends of the screws h' , which pass through slots in the work-plate A', and between the lower side of which work-plate and the heads of said screws friction-washers h^2 are preferably placed to give the plate H a frictional sliding connection with the work-plate.
- To keep the rear part of the slot in the work-plate, into which the rear part of the blade e^4 extends, closed when said blade has been adjusted so far forward (when said blade has been partly used up) that it will not fill said slot, the clamping-plate e^8 , by which the said blade is held in place, is extended down to and a little below the upper surface of the work-plate A', this clamping-plate thus serving also as a lint-guard at this point.
- It is desirable that a portion of the feed-dog should work on the side of the needle away from the operator or on what (considering the progress of the work) may be termed the "front" side of the needle, and it is also desirable, to effect the "chaining off" of the end of the seam properly at all times, that there should be no opening between the lower trimmer-blade and the feed or other support for the work adjacent to said blade. To keep the slot in the work-plate closed at the point referred to, I have provided an adjustable feed-dog c^5 , carried by an arm c^6 , which encircles the trimmer-shaft E. The auxiliary feed-dog c^5 is connected with the main feed-dog c' by means of a lip on the former engaging an undercut notch or groove in the latter, as shown in Fig. 3, and said auxiliary

feed-dog is also connected with the feed-bar through the arm c^6 , the rear end of which encircles the trimmer-shaft E, mounted in said feed-bar, and thus the said auxiliary feed-dog will move up and down and back and forth with the feed-bar and main feed-dog. The arm c^6 is pressed against the lower trimmer-blade e^5 , and the said lower blade is pressed against the upper blade e^4 and the latter held against the arm e' by the spiral spring e^{12} , interposed on the shaft E between the said arm c^6 and a nut e^{13} on the outer end of said shaft. Thus the sectional or auxiliary feed-dog c^5 while moving up and down and back and forth with the main feed-dog c' is adapted to be adjusted back and forth laterally with the trimmer-blades and will always be held in contact with the lower trimmer-blade, so as to keep the slot in the work-plate closed adjacent to said blade when the trimmer is adjusted away from the needle.

The operation of my improved trimmer is essentially the same as that shown and described in my patent hereinbefore referred to. Both blades of the trimmer being mounted on the feed-bar follow the movements thereof, the rocking upper blade closing to effect the cutting when the feed is moving forward to advance the work, and the entire trimmer, including both blades and the trimmer-operating rock-shaft, being adjustable toward or from the needle to vary the distance between the line of stitching and the line of trimming, either when the machine is in operation or at rest, as in my former patent, while the trimmer-slot in the work-plate is at all times kept closed by the lint-guards H, H', and e^3 surrounding the trimmer-blades.

Having thus described my invention, I claim and desire to secure by Letters Patent—

1. The combination with the stitch-forming mechanism of a sewing-machine, of a laterally-adjustable shear-trimmer device, a work-plate slotted for the reception of said shear-trimmer device, and a laterally-adjustable lint-guard extending closely adjacent to both sides of said shear-trimmer to close said slot, and connections between said trimmer and said guard whereby the latter will be adjusted coincidently with the former to keep the said slot closed at all times on both sides of the trimmer regardless of the position of adjustment of said trimmer.

2. The combination with the stitch-forming mechanism of a sewing-machine, of a laterally-adjustable trimmer, the guard-plate H connected with said trimmer to be laterally adjustable therewith, and the independent guard-plate H' removably attached to said plate H and adjustable therewith and with said trimmer.

3. In a sewing-machine trimmer, the combination with an operating rock-shaft, of upper and lower trimmer-blades one of which is connected with said shaft to oscillate therewith and the other of which is stationary rela-

tive to said shaft, and both of which are pivotally mounted on said shaft so that they may be adjusted about the same to compensate for wear, and means for securing both of said 5 blades in any desired positions of adjustment.

4. The combination with the stitch-forming and feed-operating mechanism of a sewing-machine, of a trimmer which is laterally adjustable relative to said stitch-forming mechanism, and a feed-dog which is laterally adjustable with said trimmer.

5. The combination with the stitch-forming mechanism of a sewing-machine, of a laterally-adjustable trimmer, a feed-bar and its 15 operating mechanism, a feed-dog which is fixed relative to said feed-bar, and a second feed-dog which is connected to and laterally adjustable with said trimmer.

6. The combination with the stitch-forming 20 and feed-operating mechanism of a sewing-machine, of a laterally-adjustable shear-trim-

mer comprising upper and lower blades, and a laterally-adjustable feed-dog placed closely adjacent to said lower blade and connected with said trimmer to be laterally adjustable 25 therewith.

7. The combination with the stitch-forming mechanism of a sewing-machine, of a laterally-adjustable shear-trimmer comprising upper and lower blades, a feed-bar and its operating mechanism, a feed-dog which is fixed relative to said feed-bar, and a second feed-dog placed closely adjacent to said lower blade and connected with said trimmer to be laterally adjustable therewith. 30

In testimony whereof I affix my signature in presence of two witnesses.

EDWARD B. ALLEN.
